S. PENKSA

SAP SPOUT

Filed Feb. 7, 1921

Inventor:
by: Stanley Penksa

Attorney

UNITED STATES PATENT OFFICE.

STANLEY PENKSA, OF LONG ISLAND CITY, NEW YORK.

SAP SPOUT.

Application filed February 7, 1921. Serial No. 443,291.

To all whom it may concern:

Be it known that I, STANLEY PENKSA, a citizen of the United States, residing at Long Island City, in the county of Queens and State of New York, have invented certain new and useful Improvements in Sap Spouts, of which the following is a specification.

This invention relates to a sap spout and has for its object to provide an improved spout especially adapted for the collection of sap from the sugar maple tree.

An object of the invention is a sap spout having a retaining means whereby the spout will be anchored to the tree.

Another object of the invention is to provide a sap spout having means whereby leakage of the sap will be prevented.

A principal object of the invention is to provide a sap spout so constructed that it must go into the tree in an inclined position in order that no sap will stand in the spout long enough to freeze as quite often happens with spouts of the usual construction.

With the above and other objects in view which will more fully appear hereinafter, I have invented the device illustrated in the accompanying drawings, in which—

30 Figure 1 is a view of a tree, partly broken away, showing my sap spout in use thereon,

Figure 2 is a similar view the tree being partly in section in order to show the entire spout construction in elevation,

35 Figure 3 is an enlarged perspective view of the spout.

Like reference characters indicate like parts throughout the following specification and in the several views in the drawings in which 1 indicates an inclined bore in a tree trunk the bore extending up from the bark toward the heart of the tree. In the bore is a sap spout 2, the inner part 3 of which is in the shape of a hollow cone 45 with relatively large cut-outs 4 and 5 in the sides thereof. Arranged at a point dividing the inner part 3 and the spout proper 6 is an annular flange 7 so positioned that when the flange is flat against the outer surface of the tree, the apex 8 of the cone must be pointing up so that the entire device is held inclined relative to the trunk of the tree, and the lips 9 of the spout at

the lowest point of the device except that of the hook 10 for a sap receptacle or bucket 11. The apex 8 is provided with a series of barbs 12 so inclined that when once driven into the body of the tree they will not pull out through any weight of the sap bucket, or said apex may be used without said barbs. Furthermore, the angle of the spout 6 relative to its conical portion 3 is such that the strain of the weight of the sap bucket is not directly against said barbs. The hook 10 on the end of the spout is thickened at 9^a and arranged to withstand blows from a hammer when being driven into the tree.

Having now described my invention that which I claim as new is:—

1. A device of the character described having a conically formed inner terminal, a spout and an annular flange at the rear of said spout, said terminal being spiked, a hollow spider formation connecting said terminal and said spout.

2. A device of the character described consisting of an inclined spout terminating in a vertical flange and means for holding said spout connected to a sap opening, said means consisting of an inclined hollow spider.

3. A device of the character described including a skeleton inner portion terminating in a cone, an inclined spout and a vertical annular flange surrounding said spout.

4. A device of the character described including a skeleton inner portion terminating in a cone, an inclined spout and a vertical annular flange surrounding said spout, and means whereby one end of said spout may be held into a tree cavity and said flange held bound against the outer edge of said cavity.

5. A device of the character described including a skeleton inner portion terminating in a cone, an inclined spout and a vertical annular flange surrounding said spout, and means whereby one end of said spout may be held into a tree cavity and said flange held bound against the outer edge of said cavity, said means consisting of inclined teeth on said cone.

6. A device of the character described consisting of an inclined spout terminating in a vertical flange and means for holding

ing said spout connected to a sap opening, said means consisting of an inclined spider, said spider terminating in a solid cone.

7. A device of the character described
5 consisting of an inclined spout terminating in a vertical flange and means for holding said spout connected to a sap opening, said means consisting of an inclined spider, said

spider terminating in a solid cone, said cone having teeth inclined toward said spider. 10

In testimony whereof I affix my signature in the presence of two witnesses.

STANLEY PENKSA.

Witnesses:

LOUIS STEIN,

W.M. F. SWEENEY.
